UNITED STATES PATENT OFFICE

WILLIAM M. MILLER, OF NORTH ATTLEBORO, MASSACHUSETTS, ASSIGNOR TO EXCEL
ROSARY & NOVELTY CO., INC., OF NORTH ATTLEBORO, MASSACHUSETTS

DESIGN FOR A NECK CHAIN OR SIMILAR ARTICLE

Application filed June 23, 1930. Serial No. 36,150. Term of patent 7 years.

To all whom it may concern:

Be it known that I, WILLIAM M. MILLER, a citizen of the United States, residing at North Attleboro, in the county of Bristol and State of Massachusetts, have invented a new, original, and ornamental Design for Neck Chain or Similar Article, of which the following is a specification, reference being had to the accompanying drawing, forming part thereof.

The figure is a front elevational view of the chain showing my new design.

The dominant feature of the invention resides in the frusto-conical members which are flared and have integral flutes extending

through their tops and bottoms, the flutes imparting a continuous wave like bottom edge to the members, combined with the balls which latter have substantially one-half thereof received within the frusto-conical members so that the bottom edges of the frusto-conical members extend outwardly beyond the sides of the balls.

I claim:

The ornamental design for neck chain or similar article, as shown and described.

In testimony whereof I have signed my name to this specification.

WILLIAM M. MILLER.
